UNITED STATES PATENT OFFICE

149,878

DESIGN FOR A TRIPOD FOR PHOTOGRAPHIC PURPOSES

George Charles Kammermeyer, St. Louis, Mo.

Application April 15, 1946, Serial No. 128,590

Term of patent 7 years

(Cl. D57—1)

To all whom it may concern:

Be it known that I, George Charles Kammermeyer, a citizen of the United States, residing at St. Louis, Missouri, have invented a new, original, and ornamental Design for Tripods for Photographic Purposes, of which the following is a specification, reference being had to the accompanying drawing, forming part thereof.

Fig. 1 is a side elevational view of a tripod for photographic purposes, showing my new design, the three legs being similar in appearance.

Fig. 2 is a plan view of the head of the tripod; and

Fig. 3 is an elevation of the head of the tripod, taken from the right of Fig. 1.

I claim:

The ornamental design for a tripod for photo-

graphic purposes, substantially as shown and described.

GEORGE CHARLES KAMMERMEYER.
